COMBINATION KEY AND CARD HOLDER

Albert L. Branch, Richmond, Va.

Application February 27, 1935, Serial No. 8,546

6 Claims. (Cl. 206—38)

This invention relates to holders and carriers for automobile registration cards, drivers' permits and such other papers as may be required to be carried by the operator of a motor vehicle 5 while driving.

Its object is to provide a carrier for the above named papers which will protect them against undue wear and tear, which will insure that the said papers are always in possession of the operator when driving and which will permit easy display of the papers when called upon by persons having a right to see them.

The laws of most jurisdictions require that operators of motor vehicles, when driving, shall have in their possession a driver's permit and a registration card showing the name and residence of the owner of the car. When carried in the driver's pocket or in a card case or purse, as they usually are, they become worn and defaced. When so carried they are not only not handy to procure when demanded by an officer, but they will be frequently forgotten when the driver changes suits.

My invention provides a carrier for such cards or papers which is in the form of a fountain pen barrel which may be carried in the pocket of the driver as he would carry a pen, the barrel being provided with means for supporting the said papers rolled up and provided with means for supporting the ignition key for the vehicle. Since the said papers and the ignition key are fastened together, the operator of the vehicle is insured that he will always have with him his driver's permit and other necessary papers when driving.

Referring to the accompanying drawing which is made a part hereof and on which similar reference characters indicate the same parts throughout.

Figure 1 is a longitudinal section showing the casing and card holder with a card or cards wound thereon.

Figure 2 is a section on line 2—2 of Figure 1.

Figure 3 is a perspective view of the card holding elements in open position, and

Figure 4 is a modified form of a key-attaching end for the casing.

In the drawing numeral 1 indicates a casing having a removable cap 2 which may be screw threaded upon the casing as shown. The other end of the casing is preferably closed. The casing is provided with a suitable clip or fastener for securing the device in the pocket of the driver, and when so carried it will resemble a fountain pen or pencil. The cap has a central opening thru

which extends a stem 4 which carries an ignition key on its outer end and the card supporting elements on its inner end.

The card supporting elements consist of a pair of resilient strips 5 and 6. One of these strips, as 6, is secured to the end of the stem 4. A convenient way of securing these elements together is by splitting the end of the stem 4 and inserting the end of the strip therein and soldering or welding it. It may be found feasible to make the strip 6 and the stem 4 of a single piece. The other ends of the strips 5 and 6 are secured together by a ring or washer 7. The ends of the strips are cut away to provide shoulder portions 8 against which the washer 7 is held. The ends of the strips may be turned over as shown at 9 to hold the washer on.

The other ends of the strips are narrowed to provide shoulder portions 10 and 11 to limit the longitudinal movement of a holding ring 12 which is positioned upon the narrowed portion of the strip 6 and is slidable to engage the narrowed end of the strip 5 and hold these strips together in card engaging position as shown in Figure 1. The stem 4 is screw threaded and has thereon a nut 13. A compression spring 14 surrounds the stem 4 and is confined between the nut 13 and the ring 12, so as to urge the ring 12 into engagement with the shoulders 10 and 11. The shoulder 11 prevents the ring 12 from being forced along the strip 6 when the parts are in open position as shown in Figure 3.

A small collar 15 is fitted around the stem 4 and a washer 16 is positioned against this collar. A nut 17 having an eye for holding an ignition key 18 is screwthreaded upon the stem and brought into engagement with the washer 16. This provides a swivel connection between the card and key holding elements and the casing.

A card 19 is held along one edge between the strips 5 and 6 and may be wound around these strips between the rings 7 and 12. The card 19 may be a driver's permit, a registration card or other papers or all of these, being shown as a single card for the purpose of simplicity only.

For inspection of the cards or permit the cap 2 is unscrewed and the parts withdrawn from the casing whereupon the cards may be unwound and inspected. When wound around the holding strips they are kept clean and dry and are not subject to any friction to deface them.

In the modified form of cap shown in Figure 4, the single cap 20 is used instead of the three parts 15, 16, and 17 shown in Figure 1. This cap has an extended portion 21 which is threaded on its

interior to receive the threaded end of the stem. The end of this extended portion engages a nut 23. The cap is provided with an eye portion 22 to receive a key or key ring, or chain. In other respects this form is the same as that shown in Figures 1 to 3.

It will be obvious to those skilled in the art that various changes may be made in the invention without departing from the spirit thereof, I therefore do not limit myself to the invention as shown in the drawing and described in the specification but only as set forth in the appended claims.

What I claim is:

1. A holder and carrier for an ignition key for a motor vehicle and a card or cards comprising a casing made to resemble the barrel of a pen, means on said casing for supporting it in upright position, a removable cap on said casing said cap having an opening therein, a card and key supporting element rotatably mounted in said opening, a card carrying element carried by said last named element, said card carrying element including a pair of resilient strips secured at one end one of said strips being loose at the other end, a ring slideable on one strip and movable to engage the loose end of the other strip to hold the strips together in card engaging position.

2. A holder and carrier for an ignition key and a driver's permit or the like comprising a casing having a cap removably secured thereon, a stem rotatably mounted in said cap, an ignition key carried on said stem exteriorly of said casing, a card holding element carried by said stem interiorly of said casing, said card holding element comprising a strip secured at one end to said stem and secured at its other end to the end of a second strip, said second strip having a free end having a narrowed portion to provide a shoulder thereon, a ring positioned on the first named strip and having means engageable therewith for moving it to engage the end of the second strip and hold the two strips in card engaging position.

3. A device as in claim 2 wherein the first named strip is provided with a shoulder portion to pre-

vent movement of the ring along the strip when the end of the second strip is released.

4. A device of the kind described comprising a casing having a removable cap thereon, a stem rotatably carried by said cap, a key holding element carried by said stem exteriorly of the casing, a card holding element carried by said stem on the inside of the said casing, said card holding element comprising a pair of resilient strips secured together at their outer ends, the other end 10 of one of the strips being secured to the said stem and having a narrowed portion, a ring carried by the said narrowed portion, a nut secured on said stem, a spring surrounding said narrowed portion and confined between the said nut and the said 15 ring, the end of the other strip being narrowed to provide a shoulder and to receive the said ring to hold said strip in card holding position.

5. A holder and carrier for an ignition key for a motor vehicle and a card or cards comprising a 20 casing, a removable cap on said casing, a key supporting element carried by one side of said cap, a card supporting element carried by the other side of the cap, said card carrying element comprising a pair of resilient strips secured together 25 at one end, one of said strips being loose at the other end and a disk slideable on one strip and movable to engage the loose end of the other strip to hold the strips together in card carrying position and to serve as a guide for one end of the 30 card.

6. A holder and carrier for an ignition key for a motor vehicle and a card or cards comprising a casing, a removable cap on said casing, a key supporting element carried by one side of said 35 cap, a card supporting element carried by the other side of the cap, said card supporting element including a pair of strips secured together at one end, one of said strips being resilient and having one free end and a disk slideable on one strip and 40 movable to hold the strips together in card engaging position.
